Primary Examiner — Lakiya G Rogers*Assistant Examiner* — John A Voytek*(74) Attorney, Agent, or Firm* — Young & Thompson(57) **CLAIM**

The ornamental design for a perfume diffuser, as shown and described.

DESCRIPTION

FIG. 1 is a top, left side perspective view a perfume diffuser showing the new design;

FIG. 2 is a top plan view thereof;

FIG. 3 is a bottom plan view thereof;

FIG. 4 is a right side elevation view thereof;

FIG. 5 is a left side elevation view thereof;

FIG. 6 is a front elevation view thereof;

FIG. 7 is a rear view thereof; and

FIG. 8 is a top and rear perspective view thereof with unclaimed environment; and,

FIG. 9 is a top and left side perspective view thereof with unclaimed environment.

The portions of the design shown in broken lines in FIG. 4 form no part of the claim. The broken lines shown in FIGS. 8 and 9 show unclaimed environmental structure of the type used with the perfume diffuser.
